(57) **CLAIM**

The ornamental design for a hair remover, as shown and described.

DESCRIPTION

FIG. 1 is a top, front and left side perspective view of a hair remover showing my new design;

FIG. 2 is a bottom, rear and right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of the portion labeled "9" in FIG. 1;

FIG. 10 is an enlarged view of the portion labeled "10" in FIG. 2;

FIG. 11 is an enlarged view of the portion labeled "11" in FIG. 2;

FIG. 12 is an enlarged view of the portion labeled "12" in FIG. 3;

FIG. 13 is an enlarged view of the portion labeled "13" in FIG. 3;

FIG. 14 is an enlarged view of the portion labeled "14" in FIG. 5; and,

FIG. 15 is an enlarged view of the portion labeled "15" in FIG. 8.

The dash-dash broken lines illustrate portions of the hair remover. The dot-dash broken lines represent the boundaries and indicators of the enlarged views. The broken lines form no part of the claimed design.

1 Claim, 15 Drawing Sheets
